Primary Examiner — Paula Greene(74) *Attorney, Agent, or Firm* — Capitol City TechLaw(57) **CLAIM**

The ornamental design for parts of Marshall monitor headphone, as shown and described.

DESCRIPTION

FIG. 1 is a front, top, and left side perspective view of parts of Marshall monitor headphone showing my new design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The broken lines shown in the figures are included for the purpose of illustrating portions of parts of Marshall monitor headphone that form no part of the claimed design.
